US0D1099104S

(12) **United States Design Patent** (10) **Patent No.:** **US D1,099,104 S**
(45) **Date of Patent:** **** Oct. 21, 2025**

(54) **SUPPORT FOR ELECTRONIC DEVICES**

(71) Applicant: **Jiajia He**, Liuzhou (CN)

(72) Inventor: **Chenglan Huang**, Liuzhou (CN)

(73) Assignee: **Jiajia He**, Liuzhou (CN)

(**) Term: **15 Years**

(21) Appl. No.: **29/907,974**

(22) Filed: **Jan. 10, 2024**

(30) **Foreign Application Priority Data**

Jul. 14, 2023 (CN) 202330442722.2

(51) **LOC (15) Cl.** **14-06**

(52) **U.S. Cl.**

USPC **D14/251**; D14/250

CLAIM

The ornamental design for a support for electronic devices, as shown and described.

DESCRIPTION

FIG. 1 is a perspective view of a support for electronic devices showing my new design;

FIG. 2 is a perspective view of a support for electronic devices showing my new design;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
